UNITED STATES PATENT OFFICE.

ALBERT JOHN DAVIES, OF SAULT STE. MARIE, ONTARIO, CANADA.

FOURDRINIER MACHINE.

1,425,240.

Specification of Letters Patent. Patented Aug. 3, 1922.

Application filed March 12, 1921. Serial No. 451,693.

To all whom it may concern:

Be it known that I, ALBERT J. DAVIES, a subject of Great Britain, residing at Sault Ste. Marie, in the Province of Ontario and Dominion of Canada, have invented a new and useful Improvement in Fourdrinier Machines, of which the following is a specification.

This invention relates to the paper-forming mechanism of a Fourdrinier machine and has particular reference to the scraper that is applied to the deckel-strap. The use of scrapers in this connection is not new with me; but I have found none in use that may be called resiliently adjustable nor do I know of any that may be adjusted or changed without danger of injury to the sheet or to the wire.

In this invention, I have so mounted the scraper that it may yieldingly engage the deckel-strap and thus follow any irregularities in the upper surface thereof. Furthermore, I provide means for adjusting the pressure of the scraper, and mechanism for removing the scraper from its contact with said strap, without the necessity of stopping the machine and without disturbing the adjustments of the scraper.

In the drawings which accompany and form part of this specification,—

Fig. 1 is a diagram, in side elevation, of the sheet-forming portion of a Fourdrinier machine, with my device attached.

Fig. 2 is a plan diagram showing the relation of the scrapers to the wire.

Fig. 3 is a detail view, in side elevation, of one form of my invention, as attached.

Fig. 4 is a plan view of Fig. 3.

Fig. 5 is a partial view of my preferred form, with parts broken away, showing the hinge open.

Fig. 6 is a side elevation, similar to Fig. 3, showing my preferred form.

The simpler form shown in Figs. 3 and 4 will first be described. The deckel-strap A and frame B may be of the usual construction. My scraper 1, preferably of leather, is mounted in a hinged clasp comprising a fixed leaf 2 and a leaf 3 hinged thereto at 4. Scraper 1 may be secured to either of these leaves or it may be hung on pins 5 (Fig. 5) and may be thus easily renewed without dismantling the device. Leaves 2 and 3 may be locked together, when in use, by a thumb-nut 6 (Fig. 3), thus clamping scraper 1 firmly in place. Leaf

2 is attached, by screws 7, to a bar 8, the latter being pivotally attached at 9 to a rock-lever 10 which, in turn, is pivotally attached at 11 to frame B. At pivot 9, a shoulder 12 is formed to limit the swing of bar 8 in one direction, and a lock-pin 13 tends to hold bar 8 against shoulder 12. Pin 13 is loosely mounted in bar 8 and has a handle 14 by which it may be lifted and turned when it is desired to swing bar 8 on pivot 9.

Underlying a portion of bar 8 and fast with rock-lever 10, is a shelf 15 which not only gives additional support to bar 8, but which is provided with a hole 16 to slidably receive pin 13 and thus form the lock. When it is desired to swing bar 8 on pivot 9, handle 14 is raised, against the action of a spring 17, until lugs 18, fast on pin 13, clear recesses 19 in bar 8, whereupon handle 14 may be operated to give a slight rotary movement to pin 13, thus causing lugs 18 to lock over the upper surface of bar 8 and hold pin 13 in raised position. This raising of handle 14 and pin 13 is sufficient to cause the latter to entirely leave hole 16, so that bar 8 may be freely swung away from shoulder 12. Spring 17 is not an essential element in this construction.

On the rear of rock-lever 10 is an upwardly projecting arm 20, the end of which is adapted to loosely surround a threaded post 21 which is fast upon a bracket 22, the latter being secured to frame B by bolts 23. A spiral spring 24 serves to keep scraper 1 in yielding contact with deckel-strap A, and a nut 25, threaded on the free end of post 21, serves as an adjustable stop to limit the downward movement of scraper 1 and bar 8.

In Fig. 6, the general construction is the same as in Figs. 3 and 4, except that post 21 is sufficiently elongated to receive a spring 24^a which counteracts spring 24. By this means, rock-lever 10 is cushioned between springs 24 and 24^a and differences in the weights of the two arms of rock-lever 10 are so compensated that the pressure of scraper 1 upon deckel-strap A may be regulated to suit the requirements of different machines or differing conditions. Also, this method provides for automatic compensation for the wear of scraper 1. Nut 25 serves as an adjustable abutment for one end of spring 24^a while a collar 30 and set-screws 31 serve a like purpose for spring

24. In this way, the pressure of scraper 1 is adjusted to any desired degree, and automatic compensation for the wear of scraper 1 is provided within reasonable limits, 5 while, at the same time, scraper 1 may be removed for examination and replaced without disturbing these adjustments or the general mountings.

Attention is called to the fact that scraper 10 1 may be disengaged from deckel-strap A by loosening thumb-nut 6 and, without employing lock-pin 13, scraper 1 may then be swung up about hinge 4; but, as this method may permit the dropping of water or other 15 parts upon the formed sheet, I consider it inadvisable while the machine is in operation, and prefer to disengage scraper 1 by employing hinge 9.

It is to be understood that I do not limit 20 myself to the precise construction shown as, for instance, a portion of bar 8 might be made elastic and thus, in itself, provide a means for disengaging scraper 1 from deckel-strap A. I prefer to provide special 25 mechanism for such disengagement, as such is required for the purpose of this invention.

Furthermore, the boss 26, shown as integral or fast with frame B, might be a separate filling piece and the pivot 11 be threaded only into the web 27 of frame B; or other changes may be made in the construction, if within the scope of the appended claims.

35. What I claim is:

1. In a Fourdrinier machine, a deckel-strap; and a frame; in combination with a scraper; means, mounted on said frame, for holding said scraper in engagement with 40 said deckel-strap; and mechanism for disengaging said scraper from said deckel-strap without deranging said mounting means.

2. In a Fourdrinier machine, a deckel-strap; and a frame; in combination with a 45 scraper; means, mounted on said frame, for holding said scraper in yielding engagement with said deckel-strap; and mechanism for disengaging said scraper from said deckel-strap without deranging said mounting 50 means.

3. In a Fourdrinier machine, a frame; a scraping member; a hinged mounting for said member; and means for securing said mounting against said frame.

55. 4. In a Fourdrinier machine, a frame; a scraping member; a hinged mounting for said member; and means for securing said mounting in elastic relation to said frame.

5. In a Fourdrinier machine, a deckel-strap; and a frame; in combination with a 60 scraping member pivotally mounted in connection with said frame and positioned to engage said deckel-strap.

6. In a Fourdrinier machine, a deckel-65 strap; and a frame; in combination with a

scraping member pivotally mounted in connection with said frame and adapted to yieldingly engage said deckel-strap.

7. In a Fourdrinier machine, a deckel-strap; and a frame; in combination with a 70 scraping member adapted to engage said deckel-strap; and adjustable means for mounting said member in connection with said frame.

8. In a Fourdrinier machine, a deckel-75 strap; and a frame; in combination with a scraping member adapted to engage said deckel-strap; adjustable means for mounting said scraper in connection with said frame; and mechanism for withdrawing said scraping member from its engagement with said deckel-strap, without deranging said adjustable means.

9. In a Fourdrinier machine, a deckel-strap; and a frame; in combination with a 85 scraper adapted to engage said deckel-strap; and means for mounting said scraper in connection with said frame, said means including a horizontal pivoting member and a vertical pivoting member.

10. In a Fourdrinier machine, a frame; a lever pivotally mounted on said frame; and a scraping member pivotally mounted on 90 said lever and adapted to engage said deckel-strap.

11. In a Fourdrinier machine, a frame; a lever pivotally mounted on said frame; and a scraping member pivotally mounted in connection with said lever and adapted to yieldingly engage said deckel-strap.

12. In a Fourdrinier machine, a frame; a lever pivotally mounted on said frame; a scraping member pivotally mounted in connection with said lever; and adjustable means for controlling said member.

13. In a Fourdrinier machine, a frame; a scraper; a hinged mounting for said scraper; and means for pivotally connecting said mounting with said frame.

14. In a Fourdrinier machine, a frame; a scraping member; and means for so connecting said member with said frame that it may be swung both vertically and horizontally.

15. In a Fourdrinier machine, a frame; a scraping member; means for so connecting 110 said member with said frame that it may be swung horizontally; and means for locking said member against such horizontal movement.

16. In a Fourdrinier machine, a scraping 120 member; a pivotal mounting for said member; and adjustable cushioning means for controlling said member.

17. In a Fourdrinier machine, a scraping member; a rock-lever; a pivotal mounting 125 for said rock-lever; cushioning means for controlling said rock-lever; and movable means for connecting said member with said rock-lever.

18. In a Fourdrinier machine, a scraping 130

- member; a rock-lever; a pivotal mounting for said rock-lever; adjustable means for controlling said rock-lever; and means for movably connecting said member with said 5 rock-lever.
19. In a Fourdrinier machine, a frame; a scraper; a hinged mounting for said scraper; and means for movably connecting said mounting with said frame.
- 10 20. In a Fourdrinier machine, a frame; a hinged scraper; and means for movably connecting said scraper with said frame; in combination with means for controlling said movable means.
- 15 21. In a Fourdrinier machine, a deckel-strap; and a frame; in combination with a scraper; means for mounting said scraper upon said frame and in engagement with said deckel-strap; mechanism for disengaging said scraper from said deckel-strap without deranging said mounting means; and compensating means for automatically taking up the wear on said scraper.
22. In a Fourdrinier machine, a deckel-25 strap; and a frame; in combination with a scraper; means for adjustably mounting said scraper in connection with said frame and in contact with said deckel-strap and compensating means for automatically taking up the wear on said scraper.
23. In a Fourdrinier machine, a frame; a scraper; a hinged mounting for said scraper; means for attaching said mounting to said frame; and a lock for said hinge.
- 35 24. In a Fourdrinier machine, a deckel-strap; and a frame; in combination with a scraper mounted in connection with said frame; and adjustable means for holding said scraper in yielding engagement with 40 said deckel-strap.
25. In a Fourdrinier machine, a deckel-strap; and a frame; in combination with scraping means mounted in connection with
- said frame and comprising a scraper adapted to elastically engage said deckel-strap; 45 a pivotal mounting for said scraper; and a lock for said pivotal mounting.
26. In a Fourdrinier machine, a deckel-strap; and a frame; in combination with scraping means mounted in connection with 50 said frame and comprising a scraper adapted to engage said deckel-strap; adjustable means for controlling said engagement; a pivotal mounting for said scraper; and a lock for said pivotal mounting. 55
27. In a Fourdrinier machine, a frame; a lever pivotally mounted on said frame; elastic means for controlling said lever; an arm pivotally mounted on said lever; a scraper mounted on said arm; and a lock for said 60 arm.
28. In a Fourdrinier machine, a frame; a lever pivotally mounted on said frame; adjustable means for controlling said lever; an arm pivotally mounted on said lever; a 65 scraper mounted on said arm; and a lock for said arm.
29. In a Fourdrinier machine, a frame; a lever pivotally mounted in connection with said frame; elastic means for controlling 70 said lever; a scraper; a hinged mounting for said scraper; and means for connecting said hinged mounting and said lever.
30. In a Fourdrinier machine, a frame; a lever pivotally mounted in connection with 75 said frame; adjustable means for controlling said lever; a scraper; a hinged mounting for said scraper; and means for connecting said hinged mounting and said lever.
- In testimony whereof, I hereby affix my 80 signature, in the presence of two witnesses.

ALBERT JOHN DAVIES.
